UNITED STATES PATENT OFFICE.

HERMAN L. WAGNER, OF MOUNT VERNON, NEW YORK, ASSIGNOR TO
UNDERWOOD TYPEWRITER COMPANY, OF NEW YORK, N. Y., A COR-
PORATION OF NEW JERSEY.

TYPE-WRITING MACHINE.

No. 848,709.

Specification of Letters Patent.

Patented April 2, 1907.

Application filed January 6, 1907. Serial No. 350,955.

To all whom it may concern:

Be it known that I, HERMAN L. WAGNER, a citizen of the United States, residing in Mount Vernon, in the county of Westchester and State of New York, have invented certain new and useful Improvements in Type-Writing Machines, of which the following is a specification.

This invention relates to the ribbon-vibrating mechanisms of type-writing machines in which the ribbon is vibrated to cover and uncover the printing-point and in which means are provided for shifting the ribbon to bring different widthwise portions thereof into use.

The object of the invention is to provide simple and inexpensive means readily attachable to existing type-Writing machines, particularly those of the well-known "Underwood" construction, for effecting the widthwise shifting of the ribbon.

The ribbon in said machine is threaded through the upper end of a vertical reciprocating vibrator, and the latter is usually attached at its lower end to a lever, which is actuated by a device provided upon the universal-bar frame, the latter reciprocating at the type-strokes. I provide for shifting said lever bodily from side to side and fix upon its opposite sides two wrists at unequal distances from its fulcrum, said wrists engageable alternately with slotted arms that are fixed upon said universal-bar frame.

The invention further consists in certain details of construction, which will be herein-after explained.

In the accompanying drawings, Figure 1 is a perspective sectional rear view of a ribbon-vibrating mechanism of an Underwood front-strike writing-machine embodying my improvements, the parts being adjusted to bring the upper border of the ink-ribbon into use. Fig. 2 is a sectional side elevation of the ribbon parts adjusted the same as at Fig. 1 and the parts being shown in full lines in normal positions. The capital shift positions of the platen and shifting frame are indicated by dotted lines. Fig. 3 is a plan illustrating the key mechanism which controls the color of the printing. Fig. 4 is a rear elevation, partly in section, showing the parts shifted to the Fig. 1 position. Fig. 5 is

a view similar to Fig. 4, but showing the parts shifted to cause the lower border or color-band upon the ribbon to cover the printing-point at the type-strokes. Fig. 6 illustrates a type striking through the upper color-band of the ribbon, and Fig. 7 is a similar view illustrating the type striking through the lower color-band.

Types 1 are mounted in a segment 2 to strike rearwardly through a ribbon 3 upon the front side of a platen 4, the ribbon usually having upper and lower color-bands 5 6. The platen is mounted in a platen frame or carriage (not shown) having a roll 7 to run upon a rail 8, and the latter is mounted upon or forms part of a shifting frame 9, which lifts the platen to the dotted-line position at Fig. 2 to enable capital types to print. The types 1 are mounted upon bars 10, which have heels 11 to operate a universal bar 12, the latter being fixed upon a table or frame 13, which reciprocates at the type-strokes. The ribbon is threaded through the upper 75 part of a carrier or vibrator 14, having at its upper end a pair of ears 15 to embrace loosely a vertical guiding-post 16. As so far described the parts are in common use on said Underwood machine.

The ribbon-carrier 14 is reciprocated up and down by an arm 17 of a lever, which is fulcrumed at 18 upon an ear 19, projecting from a bar 20, which is mounted to slide endwise or in a direction transverse to the lever 85 17 or parallel with the axis of said lever, whereby the latter is shifted from side to side, the carrier being given a slight rocking movement, as may be seen by comparison of Figs. 4 and 5, the loose engagement of the ears 15 with 90 the post 16 permitting such rocking. The invention is not, however, limited to a machine in which the lever rocks the carrier, as it is not important in all cases that the carrier should rock.

The bar 20 is slotted at one end at 21 to slide upon screws 22, threaded into the shift-rail 8, and at the other end said bar is provided with a slot 23, engaging with a stud 24 upon the shifting frame 9. The bar is thus 100 enabled to carry the lever 17 bodily from side to side, while both the bar and the lever may shift up and down with the rail 8, together with the ribbon-carrier 14 and platen 4.

- Upon one side of the lever I provide a wrist 25, to engage a vertical slot 26, formed in an arm 27, erected upon the universal-bar frame 13. Upon the other side of the lever I provide a wrist 28, engageable with a vertical slot 29, provided with an arm 30, also fixed upon the universal bar-frame 13. Said wrists are formed in an arm 31 of the lever 17, said arm 31 extending up from the fulcrum 18 between the universal-bar arms 27 and 30. By moving the bar 20 with the lever 17 31 to the right, Fig. 4, the wrist 25, which is more remote than the wrist 28 from the fulcrum 18, is moved into the slot 26, whereby the lever is given a minimum vibration at the type-strokes and the carrier 14 is thrown up only far enough to enable the upper color-band 5 to cover the printing-point.
- When the bar 20 and the lever are moved to the left, Fig. 5, the wrist 25 is withdrawn from the slot 26 and the lower wrist 28 is moved into engagement with the slot 29 in the other arm 30, whereby the lever is given a maximum vibration at the type-strokes and the carrier 14 is thrown up sufficiently to cause the lower color-band 6 to cover the printing-point.

The slots 26 and 29 are sufficiently high to accommodate the up-and-down movements of the lever caused by the up-and-down shifting of the carriage-rail 8.

At the keyboard of the machine are provided key-bearing arms 32 33 upon the front end of a horizontal rock-shaft 34, which carries at its rear end a crank 35, the latter having a wrist or projection 36 to work loosely in a slot 37 in the end of a bar 20, so that by pushing down either key the bar 20 may be shifted to either right or left, as the case may be, and the corresponding color-band caused to cover the printing-point at the type-strokes. The slot 37 extends vertically far enough to accommodate the up-and-down shifting movements of the bar 20, due to its being mounted upon the capital-shifting frame 8 9. The bar 20 is held at either extreme of its movement by means of a detent-spring 38, secured upon the framework and co-operating with a beveled detent arm or crank 39, fixed upon the rock-shaft 34.

It will be noticed that very little change is required in order to add my improvements to existing machines and that the objection heretofore experienced has been overcome, of liability of derangement or faulty action of the light and delicate parts comprising the ribbon-vibrating mechanism.

Variations may be resorted to in respect to certain features of the invention, and portions of the improvements may be used without others.

Having thus described my invention, I claim—

1. In a type-writing machine having types and a universal bar reciprocated at the type-strokes, the combination with a ribbon-carrier, of a lever connected to the carrier and provided on opposite sides with wrists at unequal distances from its fulcrum, bearings on opposite sides of said lever and engageable by said wrists and connected to said universal bar to reciprocate therewith, and means for shifting said lever from side to side to engage and disengage the wrists with the bearings.

2. In a type-writing machine having types and a universal bar reciprocated at the type-strokes, the combination with a ribbon-carrier, of a lever connected to the carrier and provided on opposite sides with wrists at unequal distances from its fulcrum, bearings on opposite sides of said lever and engageable by said wrists and connected to said universal bar to reciprocate therewith, and means for shifting said lever from side to side to engage and disengage the wrists with the bearings; said carrier extending upwardly from said lever and loosely guided at its upper portion to permit it to rock from side to side to accommodate the lateral shifting movements of the lever and also to permit it to be reciprocated up and down by the lever to cause the ribbon to cover and uncover the printing-point.

3. In a type-writing machine having types and a universal bar reciprocated at the type-strokes, the combination with a ribbon-carrier, of a lever connected to the carrier and provided on opposite sides with wrists at unequal distances from its fulcrum, bearings on opposite sides of said lever and engageable by said wrists and connected to said universal bar to reciprocate therewith, a shifter whereon said lever is mounted, said shifter movable in a direction transverse to the lever to shift the latter from side to side to engage and disengage the wrists with the bearings, a finger-piece for said shifter, and a detent for holding the shifter at either end of its movement.

4. In a type-writing machine having types and a universal bar which is reciprocated at the type-strokes, the combination of a ribbon-carrier, a lever connected to said ribbon-carrier to reciprocate the same, a shifter-bar upon which said lever is fulcrumed, said bar mounted to shift in a direction transverse to said lever, wrists projecting from opposite sides of said lever at different distances from its fulcrum, and arms connected to said universal bar, one upon each side of said lever, said arms having bearings engageable alternately by said wrists.

5. In a type-writing machine having types and a universal bar which is reciprocated at the type-strokes, the combination of a ribbon-carrier, a lever connected to said ribbon-car-

rier to reciprocate the same, a shifter-bar upon which said lever is fulcrumed, said bar mounted to shift in a direction transverse to said lever, wrists projecting from opposite sides of said lever, at different distances from its fulcrum, and arms connected to said universal bar, one upon each side of said lever, said arms having bearings engageable alternately by said wrists, and a rock-shaft having a crank connected to said bar for moving said lever from side to side to engage either of its wrists with its associated bearing and disengage the other wrist from its associated bearing, said rock-shaft extending from said bar to the front of the machine and provided at its forward end with a finger-piece.

6. In a type-writing machine having types and a universal bar which is reciprocated at the type-strokes, the combination of a ribbon carrier, a lever connected to said ribbon-carrier to reciprocate the same, a shifter-bar upon which said lever is fulcrumed, said bar mounted to shift in a direction transverse to said lever, wrists projecting from opposite sides of said lever, at different distances from its fulcrum, and arms connected to said universal bar, one upon each side of said lever, said arms having bearings engageable alternately by said wrists, a rock-shaft having a crank connected to said bar for moving said lever from side to side to engage either of its wrists with its associated bearing and disengage the other wrist from its associated bearing, said rock-shaft extending from said bar to the front of the machine and provided at its forward end with a finger-piece, a detent-arm upon said rock-shaft, and a detent-spring upon the framework engaging said arm to hold the bar at either end of its movement.

40 7. In a type-writing machine provided with a framework and also having types and a universal-bar frame which is reciprocated at the type-strokes, the combination of a ribbon-carrier which is loosely guided near one end both for reciprocatory movement to cause the ribbon to cover and uncover the printing-point and also for a lateral rocking movement, a lever connected to the other end of said ribbon-carrier to reciprocate the same, a bar upon which said lever is fulcrumed, said bar mounted to move in a direction transverse to said lever, wrists projecting from opposite sides of said lever at different distances from its fulcrum on said bar, arms upon said universal frame, one upon each side of said lever, said arms having bearings engageable alternately by said wrists, a rock-shaft having a crank loosely connected to said bar for moving said lever from side to side to engage either of its wrists with its associated bearing and disengage the other wrist from its associated bearing, said rock-shaft extending from said bar to the front of the machine and provided at its forward end

with a finger-piece, a detent-arm upon said rock-shaft, and a detent-spring upon the framework engaging said arm to hold the bar at either end of its movement.

8. In a type-writing machine having types, a universal bar reciprocated at the type-strokes, a platen and a frame whereon said platen shifts for writing capital and lower-case letters, the combination with a ribbon-carrier, of a lever connected to the carrier and mounted upon said shifting frame to shift therewith together with the ribbon-carrier, said lever provided on opposite sides with wrists at unequal distances from its fulcrum, slotted arms on opposite sides of said lever and engageable by said wrists at all positions to which said frame is shifted and connected to said universal bar to reciprocate therewith, and means mounted upon said shifting frame for also shifting said lever from side to side to engage and disengage the wrists with the slotted arms.

9. In a type-writing machine having types, a universal bar reciprocated at the type-strokes, a platen and a frame whereon said platen shifts for writing capital and lower-case letters, the combination with a ribbon-carrier, of a lever connected to the carrier and mounted upon said shifting frame to shift therewith together with the ribbon-carrier, said lever provided on opposite sides with wrists at unequal distances from its fulcrum, slotted arms on opposite sides of said lever and engageable by said wrists at all positions to which said frame is shifted and connected to said universal bar to reciprocate therewith, a shifter whereon said lever is mounted, said shifter mounted on said shifting frame and also movable in a direction transverse to the lever to shift the latter from side to side to engage and disengage the wrists with the slotted arms, and a finger-piece upon the framework of the machine and loosely engaged to said shifter to accommodate the movements of said shifting frame.

10. In a type-writing machine having types, a universal bar reciprocated at the type-strokes, a platen and a frame whereon said platen shifts for writing capital and lower-case letters, the combination with a ribbon-carrier, of a lever connected to said ribbon-carrier to reciprocate the same, a shifter-bar upon which said lever is fulcrumed, said bar mounted on said platen-shifting frame to shift also in a direction transverse to said levers, wrists projecting from opposite sides of said lever at different distances from its fulcrum, arms connected to said universal bar one upon each side of said lever, said arms having slots extending in the direction of the shifting movement of said platen and engageable alternately by said wrists, a rock-shaft mounted upon the framework and having a crank loosely con-

nected to said bar to accommodate the platen-shifting movements of said frame, for enabling said shaft to move said bar and said lever from side to side to engage either of its wrists with its associated slot and disengage the other wrist from its associated slot, said rock-shaft extending from said bar to the

front of the machine, and a finger-piece upon the forward end of said rock-shaft.

HERMAN L. WAGNER.
